(57) **CLAIM**

The ornamental design of a trailer coupler, as shown and described.

DESCRIPTION

FIG. 1 is a front perspective view of the trailer coupler showing my new design;

FIG. 2 is a front perspective view of the design shown in FIG. 1 with the latch in its open position. The section removed is exactly the same as the opposite side of the moveable latch.

FIG. 3 is a front perspective view with a cutout of the latch illustrating the pin insertion to lock the latch in place. The section removed is exactly the same as the opposite side of the moveable latch.

FIG. 4 is a top plan view of the design shown in FIG. 1; FIG. 5 is a side plan view of the design shown in FIG. 1; FIG. 6 is a second side plan view of the design shown in FIG. 1;

FIG. 7 is front plan view of the design shown in FIG. 1; FIG. 8 is a bottom plan view of the design shown in FIG. 1; and,

FIG. 9 is a front perspective view of the design of the trailer coupler with the latch in the closed position.
